CLAIM

The ornamental design for data processing equipment, as shown and described.

DESCRIPTION

FIG. 1 is a front view of data processing equipment in accordance with our new design;

FIG. 2 is a rear view thereof;

FIG. 3 is a top plan view thereof;

FIG. 4 is a bottom view thereof;

FIG. 5 is a right side elevation view thereof;

FIG. 6 is a left side elevation view thereof; and,

FIG. 7 is a front perspective view thereof.

The broken lines in the drawings are for the purpose of illustrating environmental structure and illustrate portions of the data processing equipment which form no part of the claimed design.
